UNITED STATES PATENT OFFICE.

JAMES H. HERRON, OF ERIE, PENNSYLVANIA, ASSIGNOR TO HERRON & BURY MANUFACTURING COMPANY, OF ERIE, PENNSYLVANIA, A CORPORATION OF PENNSYLVANIA.

AIR-COMPRESSOR GOVERNOR.

SPECIFICATION forming part of Letters Patent No. 736,258, dated August 11, 1903.

Application filed October 6, 1902. Serial No. 126,220. (No model.)

To all whom it may concern:

Be it known that I, JAMES H. HERRON, a citizen of the United States, residing at Erie, in the county of Erie and State of Pennsylvania, have invented certain new and useful Improvements in Air-Compressor Governors; and I do hereby declare the following to be a full, clear, and exact description of the invention, such as will enable others skilled in the art to which it appertains to make and use the same, reference being had to the accompanying drawings, and to the characters of reference marked thereon, forming part of this specification.

15 My invention relates to governors for air-compressors; and it consists in mechanism for controlling the pressure of the output of compressed air so that when it rises to a predetermined pressure the inlet-valves of the cylinder are automatically raised from their seats, so that the air in the cylinder remains at atmospheric pressure during the operation of the piston until the pressure in the receiver is reduced to the predetermined pressure, 25 when the inlet-valves again return to their seats and become operative, as before.

The features of my invention are herein-after set forth and described, and illustrated in the accompanying drawings, in which—

30 Figure 1 is a side view in elevation of an air-compressor cylinder and receiving-tank with the inlet-valve mechanism of the cylinder in section. Fig. 2 is an enlarged vertical section of the governing-valve mechanism of my device on the line xx in Fig. 4. Fig. 3 is another vertical section on the line xx in Fig. 4 with the valve in a raised position without the weight-yoke. Fig. 4 is a cross-section of the same on the line yy in Figs. 2 35 and 3 with the plunger and weight-yoke removed. Fig. 5 is a vertical section of the same on the line zz in Fig. 4 with the valve-shell removed. Fig. 6 is a like section on the line xx in Fig. 4. Fig. 7 is a vertical section 40 of the valve-shell. Fig. 8 is a view in elevation of the valve. Fig. 9 is a view in elevation of the valve.

In the drawings illustrating my invention, A is a compressor-cylinder, B a receiving-tank connected by a pipe C with the cylinder-discharge-valve mechanism, C' the in-

let-pipe, and D D the air-inlet valves, all of the usual and ordinary construction.

On the side of the cylinder A, I secure a valve-case E, from the lower part of which a pipe b extends to the receiver B, so that the compressed air is supplied thereto at the same pressure as that of the air in the receiver B, and on the lower ends of the valve-casings of the valves D D, I secure plunger-cylinders D' D' in line with the stems of the valves D D, in which cylinders I place plungers d d, adapted when raised to contact with the lower ends of the stems of the valves D D and raise them off of their seats a a, and from a passage E' (see Figs. 1 and 4) in the back of the upper part of the valve-case E pipes F F lead down to and into the lower ends of the plunger-cylinders D' D', as clearly shown in Fig. 1.

The valve-case E is provided with a lower chamber e, which is always in communication with the pipe or passage b and with the lower part of the case. The valve-case E has also an upper chamber e², which is constantly in communication with the atmosphere by holes e³. The valve-case E has also a middle chamber e', provided with branches 4 and 5, which overlap the lower and upper chambers, but which are arranged out of line with them. A passage E' connects the middle chamber constantly with the pipes F.

H is a valve-shell secured in the case E and provided with holes h', connecting with the lower chamber e, and holes h, arranged between the holes h' and connecting with the branch 4 of the middle chamber. The valve-shell has holes h², connecting with the branch 5 of the middle chamber, and holes h³ between the holes h² and connecting with the upper chamber. The lower end of the valve-shell is constantly open to the lower chamber e.

I is the valve, which is slidable in the valve-shell H and which has a head I', which normally rests on the top of the valve-shell, and two circumferential grooves i and i'.

J is a yoke which rests on top of the valve I and which is provided with adjustable weights J' for holding down the valve.

When the valve is in its normal position, as shown in Fig. 2, the air-pressure in the re-

ceiver B extends through the pipe b into the lower chamber e and under the valve I. The pipes F at this time are connected with the atmosphere by the passage E', middle chamber e' , hole h^2 , valve-groove i , hole h^3 , upper chamber e^2 , and hole e^3 . The valves D are therefore operative. When the pressure in the receiver B exceeds a prearranged limit, the valve I is forced upward to the position shown in Fig. 3. The air from passage b now passes from the lower chamber e through hole h' , valve-groove i' , hole h , branch 4 of middle chamber e' , through said chamber e' , and passage E' to the pipes F, and its pressure raises the plungers d, and thereby renders the valves D inoperative until the pressure in the receiver B again becomes normal. When the valve I is raised, the connection between the pair of holes h^2 and h^3 is cut off, and when the valve I is down the connection between the pair of holes h' and h is cut off.

What I claim is—

1. The combination, with a compressed-air receiver, and plunger-cylinders provided with plungers for raising the valves of an air-compressor; of a governor-valve case, a pipe between the said valve-case and receiver, pipes between the said valve-case and cylinders, a valve-shell secured in the said case and provided with holes arranged in pairs and a loaded governor-valve slideable inside the said valve-shell and normally connecting the said cylinders with the atmosphere, said valve and its case being provided with suitable air-pas-

sages substantially as set forth which operate normally to connect the said cylinders with the atmosphere, through one pair of holes in the said valve-shell and to connect the said cylinders with the said receiver when the said valve is slid from its normal position by the pressure of the air in the said receiver, through the other pair of holes in the said valve-shell.

2. The combination, with a governor-valve casing provided with a lower chamber and an inlet for compressed air connected with the said chamber, an upper chamber connected with the atmosphere, and a middle chamber having branches which overlap the said lower and upper chambers; of a valve-shell secured in the said case with its lower end open to the said lower chamber, said valve-shell being also provided with holes arranged in pairs for connecting the said lower and upper chambers respectively with the said middle chamber, outlet-pipes connected to the said middle chamber, and a loaded governor-valve slideable in the said valve-shell and provided with grooves for connecting together the pairs of holes in the said valve-shell, substantially as set forth.

In testimony whereof I affix my signature in presence of two witnesses.

JAMES H. HERRON.
